(57) **CLAIM**

The ornamental design for a table leg, as shown and described.

DESCRIPTION

FIG. 1 is a perspective view of a table leg in a first embodiment showing my new design, the broken lines represent environment and form no part of the claimed design;

FIG. 2 is a perspective view of the table leg of FIG. 1;

FIG. 3 is a front view of the table leg of FIG. 1;

FIG. 4 is side view of the table leg of FIG. 1;

FIG. 5 is a top view of the table leg of FIG. 1;

FIG. 6 is a bottom view of the table leg of FIG. 1;

FIG. 7 is a perspective view of a table leg in a second embodiment showing my new design, the broken lines represent environment and form no part of the claimed design;

FIG. 8 is a perspective view of the table leg of FIG. 7;

FIG. 9 is a front view of the table leg of FIG. 7;

FIG. 10 is a side view of the table leg of FIG. 7;

FIG. 11 is a top view of the table leg of FIG. 7; and,

FIG. 12 is a bottom view of the table leg of FIG. 7.

The broken lines represent environment and form no part of the claimed design.
